LAMP

William E. Curry, 9314 Trask Ave., Playa Del Rey, Calif.

Filed Aug. 26, 1964, Ser. No. 81,439

Term of patent 14 years

(Cl. D48—20)

FIG. 1

FIGURE 1 is a front elevational view of a lamp showing my new design, the undisclosed sides and rear being substantially identical with the front elevation; and

The bottom of the lamp contains elevating feet uniformly spaced near the peripheral edge thereof as best shown in FIGURE 1.

I claim:

The ornamental design for a lamp, substantially as shown and described.
